UNITED STATES PATENT OFFICE.

GEORGE W. ROBINSON, OF CAMDEN, NEW YORK.

MOCCASIN.

1,135,622.

Specification of Letters Patent. Patented Apr. 13, 1915.

Application filed May 2, 1914. Serial No. 836,001.

To all whom it may concern:

Be it known that I, GEORGE W. ROBINSON, a citizen of the United States, residing at Camden, in the county of Oneida and State of New York, have invented certain new and useful Improvements in Moccasins, of which the following is a specification, reference being had therein to the accompanying drawings.

10 My invention relates to an improved moccasin, and I declare that the following is a full, clear, concise and exact description thereof, sufficient to enable one skilled in the art to make and use the same, references 15 being had to the accompanying drawings in which like reference characters refer to like parts throughout.

While the invention is classified as that of a moccasin it is an improvement which is 20 applicable to other articles of foot-wear.

In the drawings Figure 1 is a perspective view of a moccasin showing my improvement; Fig. 2 is a perspective view showing a modification in the use of my improvement, while Fig. 3 is a further modification, and Fig. 4 is a plan view taken from Fig. 1 25 with the upper part of the moccasin broken away so as to show the two folds or plies of leather which form the hindmost portion 30 of the moccasin.

Referring to the figures in detail, A represents the side and bottom portions of the moccasin which are presumably made out of a single piece of leather with the sides 35 turned up and attached to the top forward portion B which may be suitably ornamented, the free end of which terminates in a flap D to lie on the instep. The parts A and B are formed and united in any suitable 40 manner. At the top edge of part A, however, and along a line represented by d is attached an over-top, as it may be called, which turns over the top of the part A and depends on the outside of the foot portion 45 and is indicated at F. This overfold F overhangs the top edge of the blank A from the end of top B on one side around to the opposite edge on the other side.

It is natural ordinarily that the open part 50 of the moccasin, into which the foot is inserted, because stretched so that the moccasin is not held tightly onto the foot. In order to meet this objection I have provided that the thong which forms the bow over

the instep shall pass around in and out 55 through this overhang F so that it may be tightened up to compensate for the stretching of the moccasin by the use thereof. This thong is represented by H and in Fig. 1 is illustrated as passing in and out through 60 the overhang and coming out from the overhang at the front part of the foot whence it passes under the flap D and out at the center to form the tie G.

In Fig. 2 the thong is shown as passing 65 over the edge of the flap D and thence taking a turn in the flap and out again. In this form of construction it is seen that the thong will be entirely out of the way of the foot when inserted in the moccasin. 70

In Fig. 3 is shown a different construction in which the thong H passes into the interior of the moccasin and then outward, but this is thought to be a less desirable construction than those shown in Figs. 1 and 2. 75

In Fig. 4 I show a plan view showing that the thong at the heel portion may be arranged so as to bear more directly against the foot than in the case shown in Fig. 1 where the thong passes along the outer surface of the overhanging portion. 80

It will be evident that when the moccasin has been worn for a time it may become loose to the foot and that the thong may then be tightened in the bow-knot G over 85 the instep. It is also evident that by my improvement the thong is removed entirely from contact with the foot and there is thus no inconvenience to the wearer when putting on the moccasin. This is also seen from 90 the illustration in Fig. 3 where the thong is shown as partially extending across the moccasin on its interior and more in the way of the wearer than in the illustrations shown in Figs. 1 and 2. 95

Having described my invention, what I claim as new and desire to secure by Letters Patent, is:

1. In a moccasin, the combination with a side portion, of an overhanging member 100 and a gathering thong passing in and out through said member only, the ends of which are adapted to form a tie over the instep.

2. A moccasin having its opening surrounded by an overhanging portion, and a thong passing in and out through said overhanging portion only and at the heel lying 105

next to the body of the moccasin, the ends of the thong coming together over the instep and adapted to form a tie.

3. A moccasin having its opening surrounded by an overhanging portion, and a thong passing in and out through said overhanging portion only and at the heel lying next to the body of the moccasin, the ends

of the thong coming together through the toe piece of the moccasin and forming a tie. 10

In testimony whereof I hereunto affix my signature in the presence of two witnesses.

GEORGE W. ROBINSON.
